Primary Examiner—James M. Gandy*Assistant Examiner*—Robert M. Spear[57] **CLAIM**

The ornamental design for a stand, as shown and described.

DESCRIPTION

FIG. 1 is a front elevational view of the stand showing my new design;

FIG. 2 is a rear elevational view thereof;

FIG. 3 is a right view thereof;

FIG. 4 is a left view thereof;

FIG. 5 is a top plan view thereof; and,

FIG. 6 is a bottom plan view thereof.

The stand is shown broken away in the middle to indicate indeterminate length.
